CLAIM

The ornamental design for a storage cabinet, as shown and described.

DESCRIPTION

FIG. 1 is a perspective view of a storage cabinet according to a first embodiment showing the new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view taken from the encircled area 9 of FIG. 1;

FIG. 10 is an enlarged detail view taken from the encircled area 10 of FIG. 1;

FIG. 11 is an enlarged detail view taken from the encircled area 11 of FIG. 2;

FIG. 12 is a perspective view of a storage cabinet according to a second embodiment;

FIG. 13 is another perspective view thereof;

FIG. 14 is a front view thereof;

FIG. 15 is a rear view thereof;

FIG. 16 is a left side view thereof;

FIG. 17 is a right side view thereof;

FIG. 18 is a top view thereof;

FIG. 19 is a bottom view thereof;

FIG. 20 is an enlarged detail view taken from the encircled area 20 of FIG. 12;

FIG. 21 is an enlarged detail view taken from the encircled area 21 of FIG. 12; and,

FIG. 22 is an enlarged detail view taken from the encircled area 22 of FIG. 13.

(Continued)

The broken lines shown in the figures are for the purpose of illustrating portions of the storage cabinet and form no part of the claimed design.
